John E. Hubbell
ATTORNEY

UNITED STATES PATENT OFFICE.

LOUIS WILPUTTE, OF NEW ROCHELLE, NEW YORK, ASSIGNOR OF TWO-THIRDS TO
ALICE A. WILPUTTE, OF NEW ROCHELLE, NEW YORK.

COKE OVEN.

Application filed August 12, 1922. Serial No. 581,313.

To all whom it may concern:

Be it known that I, LOUIS WILPUTTE, a citizen of the United States, and resident of New Rochelle, in the county of Westchester and State of New York, have invented certain new and useful Improvements in Coke Ovens, of which the following is a specification.

My present invention relates to coke ovens, and particularly to the well-known and widely used type in which horizontally elongated coking chambers are separated by heating walls provided each with a series of vertical flues, and in which horizontal fuel gas channels are formed in the masonry of the oven structure, beneath the vertical heating flues, and communicate with the latter through ports distributed along the length of the channels. In ovens of this type difficulty has always been experienced from the leakage out of the outer portion of the gas supply channels into the atmosphere, and into adjacent portions of the oven chambers, and into the heating flues themselves, and into the adjacent regenerators, this leakage resulting from the thermal expansion and contraction of the oven masonry, which opens the brick joints and creates cracks through which this leakage may occur. The object of this invention is to substantially eliminate this leakage, and this object I obtain by lining the outer end of each masonry gas supply channel proper with a metallic pipe formed with ports registering with the brick work ports leading to the adjacent heating flues.

The various features of novelty characterizing my invention are pointed out with particularity in the claims annexed to and forming a part of this specification. For a better understanding of my invention, however, and the advantages possessed by it, reference should be had to the accompanying drawings and descriptive matter in which I have illustrated and described a preferred embodiment of my invention.

Of the drawings:

Fig. 1 is a section taken transversely to the coking chambers through a portion of a coke oven battery, and

Fig. 2 is a partial section taken on the line 2—2 of Fig. 1.

In the coke oven shown in the drawings, horizontally elongated coking chambers A are separated by heating walls formed with

vertical flues C. The various flues C in each heating wall communicate at their upper ends with a so-called upper horizontal channel D. The heating walls proper are supported by pillar walls b between which are regenerator chambers E. The latter alternately supply pre-heated air to, and receive products of combustion from the lower ends of the flues C through ports E' shown in part in Fig. 2. At the base of each heating wall there is formed in the oven brick work, one or more gas supply channels G. In coke ovens of the general type illustrated, there are usually something like thirty heating flues C in each heating wall B, which in ordinary practice in this country is about 40 feet long, and there are two gas supply channels G at the base of each heating wall, the two channels extending into the oven structure from the opposite ends of the heating wall, each being approximately half as long as the heating wall. Each channel G is connected by corresponding ports H formed in the oven brick work with the vertical flues C above the channel. In so far as above described, the coke oven construction illustrated embodies nothing now novel with me, but on the contrary, is of a well-known and widely used type.

In accordance with the present invention the outer portion of each gas supply channel G is lined with a tubular member K formed of metal which will ordinarily be cast iron. As shown in Fig. 2, each element K extends into the oven structure from the outer side face of the battery past the masonry ports H communicating with the two flues C adjacent the corresponding end of the heating wall. Each member K is formed with lateral ports K' registering with the corresponding masonry ports H. Advantageously, the internal diameter of the metallic tubular part K is substantially the same as that of the portion of the masonry gas channel G at the inner end of the port K. The outer end portion of each channel G is enlarged sufficiently to receive the metallic member K, and to provide a space between the outer wall of the latter and the surrounding brick work to receive a suitable cement or mortar filling L. The latter may be put into place by grouting. Advantageously, also, the outer end portion of each tubular part K is enlarged to form a head K² which is internally threaded for 110

connection to a corresponding branch M from the external gas supply piping.

In the operation of an oven of the type illustrated, the expansion and contraction resulting from changes in temperature produce relative movements of the bricks forming the oven structure which tend to open the joints between the bricks and thereby cause leakage. With the particular type of construction shown, in which each channel G is formed by the aligned central passages in heavy fire brick blocks X, the leakage difficulties resulting from expansion and contraction of the oven brick work are largely due to the opening of the vertical joints Y between the blocks X. This joint opening and resulting leakage is mainly confined to the outer portions of each heating wall, where the temperature changes are most marked, and for obvious mechanical reasons the thermal expansion and contraction of the parts tends most strongly to produce joint opening movements of the brick parts.

The metallic tubular linings K provided in the outer ends of the gas channels G, will not prevent the brick work joints from opening under the conditions which have heretofore caused those joints to open, but they do, substantially minimize objectionable leakage when the brick work joints adjacent the linings open. To appreciate this it must be borne in mind that in a furnace structure such as a coke oven, there is, in general, no possibility of making the structure gas tight in any absolute sense. The refractory material available for use in the mortar placed between the bricks is not of a character which enables the mortar to form an impervious bond thoroughly cementing the bricks together. In such a structure, as a practical proposition, gas leakage is not prevented because the mortar cements the bricks together, but because the joints provide leakage paths of such relatively considerable length, and of such thinness that with the gas pressure differentials prevailing, the leakage is normally insignificant in amount under any conditions, and after relative movement of the bricks sufficient to create appreciable leakage, these paths normally tend to close up with dust, or with carbonaceous material carried into the joints by the gas.

With the present invention leakage from the portions of the gas channels G at which leakage is most apt to occur, is substantially eliminated, primarily because the leakage paths of flow from each gas channel proper into the joints Y adjacent the outer end of the heating wall, must include considerable portions of the joints between the metallic lining parts K and the surrounding brick work. The last mentioned joints elongate the leakage paths, and moreover these joints may be sealed by the grouting or ce-

ment L as efficiently as it is possible to close joints in an oven structure. The metallic parts K, connected as they are to the gas supply piping or gas guns M proper, eliminate leakage difficulties heretofore experienced from a practical inability to maintain tight joints between the inner ends of the external metallic gas gun proper and the outer ends of the masonry channels into which these guns have been inserted for a few inches.

Those skilled in the art will readily understand the practical merit and importance of my invention, since leakage from the gas supply channels to the outer end surfaces of the battery where the gas frequently burns back of the oven buckstays, and leakage from the gas supply channels into the regenerators, or into the oven chambers, or into the heating flues has frequently been a source of annoyance and inefficient combustion, and in some cases has resulted in serious injury to the oven structure. It might be thought that leakage from the gas supply channels into the combustion flues C would not be a matter of any particular importance, but this is not the case. In order to insure the proper relative supplies of air and gas at the bottom of each combustion flue, required for efficient combustion, and to obtain the proper distribution of heat imparted to each coking charge from the various heating flues in the adjacent heating walls, it is necessary to very carefully proportion the combustible gas supplies to the different flues C. This proportioning is effected, in an oven of the type shown by nozzle members I removably inserted in the upper ends of the ports H. The nozzles I provide measuring orifices which must be very accurately proportioned. The actual cross sectional area of the orifices in each nozzle is commonly of the order of a half of one square inch, and for really efficient operation the orifices in the different nozzles in each heating wall must not be of uniform size, but are graduated to suit the requirements. A relatively small amount of leakage from the gas supply channels G into the heating flues C adjacent the outer ends of the oven, may thus materially affect the heat distribution and the efficiency of combustion, and this leakage sometimes results in a very substantial reduction in the amount of surplus gas recovered in the portion of a by-product coke oven.

While the temperatures in the combustion flues C, in oven chambers, and in regenerative spaces adjacent the gas supply channels, may be, and ordinarily are, in the neighborhood of, or above 2000°, the temperatures in the outer ends of the gas supply channels G which are cooled during each alternate period of one half hour or so, (depending on the frequency with which the direction of

flow through the regenerators is reversed) by the gas then flowing through the channels, are not sufficiently high to effect rapid deterioration of the metallic parts K, when 5 the latter are formed of cast iron or similar relatively refractory metal. In case of excessive deterioration, the construction disclosed permits the replacement of the damaged lining parts K, by new lining 10 parts.

While in accordance with the provisions of the statutes I have illustrated and described the best form of my invention now known to me, it will be apparent to those skilled in the 15 art that various changes may be made without departing from the spirit of my invention as set forth in the appended claims, and that certain features of my invention may sometimes be used to advantage without a 20 corresponding use of other features.

Having now described my invention, what I claim as new and desire to secure by Letters Patent, is:

1. In a by-product coke oven, comprising 25 horizontal elongated coking chambers and interposed heating walls formed with vertical heating flues and formed with horizontal gas supply channels extending into the oven brick work from the ends of the heat-

ing walls adjacent the lower ends of the 30 heating flues and communicating with the latter through masonry ports distributed longitudinally of the channels, the improvement which consists of tubular metallic lining parts for the outer end portions of said 35 channels and formed with lateral ports registering with the adjacent masonry ports.

2. In a by-product coke oven, comprising horizontal elongated coking chambers and interposed heating walls formed with vertical 40 heating flues and formed with horizontal gas supply channels extending into the oven brick work from the ends of the heating walls adjacent the lower ends of the heating flues and communicating with the 45 latter through masonry ports distributed longitudinally of the channels, the improvement which consists of tubular metallic lining parts for the outer end portions of said channels, said parts being formed with lateral ports registering with the adjacent masonry ports, and having provisions at 50 their outer ends for connection to the external gas supply piping.

Signed at New York, in the county of 55 New York and State of New York, this 11th day of August A. D. 1922.

LOUIS WILPUTTE.
